UNITED STATES PATENT OFFICE

155,619

DESIGN FOR A COMBINATION JUVENILE
SEAT AND BOX FOR TOYS OR SIMILAR
ARTICLES

Morris Miller, Roxbury, Mass., assignor to Bancroft-Rellim Corp., Boston, Mass., a corporation of Massachusetts

Application July 13, 1948, Serial No. 147,513

Term of patent 14 years

(Cl. D15—8)

To all whom it may concern:

Be it known that I, Morris Miller, a citizen of the United States, residing at Roxbury, Boston, Massachusetts, in the county of Suffolk and Commonwealth of Massachusetts, have invented a new, original, and ornamental Design for Combination Juvenile Seat and Box for Toys or Similar Articles, of which the following is a specification, reference being had to the accompanying drawing, forming part thereof.

Fig. 1 is a side perspective view of a combination juvenile seat and box for toys or similar articles, showing my new design; and

Fig. 2 is a fragmentary sectional view on line 2—2 of Fig. 1, showing particularly the removable cover of the box.

The appearance of the opposite side of the article is similar to that shown in Fig. 1.

I claim:

The ornamental design for a combination juve-

nile seat and box for toys or similar articles, substantially as shown and described.

MORRIS MILLER.
